UNITED STATES PATENT OFFICE.

ABRAHAM HIRSCH, OF JERSEY CITY, NEW JERSEY.

SALT-BOX.

SPECIFICATION forming part of Letters Patent No. 434,083, dated August 12, 1890.

Application filed June 12, 1890. Serial No. 355,176. (No model.)

To all whom it may concern:

Be it known that I, ABRAHAM HIRSCH, of Jersey City, county of Hudson, and State of New Jersey, a citizen of the United States of 5 America, have invented certain new and useful Improvements in Salt-Boxes, of which the following is a specification.

This invention relates to an improved salt-box for kitchen use, which box is made of 10 sheet metal and lined with wood, so as to keep the salt dry and prevent the packing of the same in the box; and the invention consists of a sheet-metal salt-box in which the front wall, bottom, and rear wall of the body are 15 made integral with an upward extension of the rear wall that is provided with an opening for suspending the salt-box, said extension and the upper edge of the body being re-enforced by a wire that is bent at right angles at the connection of the body with the rear wall, as will be fully described herein- 20 after, and finally pointed out in the claims.

In the accompanying drawings, Figure 1 represents a perspective view of my improved 25 salt-box. Fig. 2 is a vertical transverse section, and Fig. 3 a front view, of the same.

Similar letters of reference indicate corresponding parts.

Referring to the drawings, A represents 30 the sheet-metal body of my improved salt-box, which body is preferably made of rectangular cross-section and formed of three pieces, one piece comprising the front wall a_1 , bottom a_1' , and rear wall a_2 , which are made 35 in one piece, while the remaining two pieces b form the side walls, which are soldered to the edges of the front wall, bottom, and rear wall, as shown clearly in Figs. 1 and 3. The rear wall a_2 is extended for a suitable length 40 above the lid B and provided with an opening a_4 , by which the salt-box may be suspended from a hook or nail on the wall. The upper edge of the body A and the edges of the extension a_3 of the rear wall a_2 are re- 45 enforced by a wire d , around which the upper edges of the body A and of the extension a_3 are folded, said wire being bent at right angles at the point where the upper edge of the body meets the rear wall a_2 , and serving to 50 impart the necessary strength to the body and extension of the box. The body A, as

well as the under side of the lid B, is covered with a lining of wood A' B' , which serves for the purpose of keeping the salt in the box in dry condition, so as to prevent the caking 55 or packing of the same. The wood lining B' of the lid B is rabbeted at the edges, so as to form a seat that rests on the upper edge of the wood lining A' of the box A, while the lid B itself extends over the edge of the body 60 A, as shown clearly in Figs. 2 and 3. In this manner a tight joint between the lid and body is formed, whereby the salt is protected to some extent against the influence of the moisture in the air and prevented from caking 65 in the box. The hinge-connection between the lid B and the extension a_3 of the rear wall of the body A is formed by lugs e and e' , which are bent up, respectively, from the lid B and extension a_3 , and of pivots e^2 70 and washers e^3 , that are interposed, respectively, between the enlarged heads of the pivots e^2 and the lugs e and e' . The wood lining A' of the body A is formed in the nature of a box open at the top which is slid into the 75 body A, while the wood lining of the lid B is riveted to the latter, as shown in Figs. 1 and 3.

My improved construction of salt-box is also adapted for bread-boxes and similar structures, in which case, however, the extension- 80 wall a_3 is dispensed with.

The advantages of my improved salt-box are, that owing to the wood lining of the box and lid, and the tight closing of the latter, the salt is kept dry and prevented from absorbing 85 moisture so as to cake; secondly, that a box of this construction is more durable than the wooden boxes in use, which, after some time, shrink and go to pieces while also giving a free access of air, so that the salt is 90 not kept dry enough for use; thirdly, that by japanning the exterior of the box in the nature of the ordinary spice-boxes in general use, the salt-box is in keeping with the exterior appearance of the other sheet-metal 95 boxes in use in the kitchen.

Having thus described my invention, I claim as new and desire to secure by Letters Patent—

1. A salt-box consisting of a sheet-metal 100 body and a lid hinged to said body, said body being formed of three pieces, a main piece

comprising the front wall, bottom, and rear wall and the upward extension of the latter, and two side walls which are soldered to the sides of the main piece, and a re-enforcing wire extending along the upper edges of the body and the edges of the exteusion, substantially as set forth.

2. A salt-box consisting of a sheet-metal body having an interior lining of wood, a hinged lid of sheet metal, having also a wood lining attached to the lid, said sheet-metal

body being provided with an extension of its rear wall, which is made integral with the front wall, bottom, and rear wall, substantially as set forth.

In testimony that I claim the foregoing as my invention I have signed my name in presence of two subscribing witnesses.

ABRAHAM HIRSCH.
